UNITED STATES PATENT OFFICE.

OTTO ERNEST DENIVELLE, OF MOUNT VERNON, NEW YORK.

SLEEPING-EYES FOR DOLLS.

1,156,761.

Specification of Letters Patent. Patented Oct. 12, 1915.

Application filed December 15, 1914. Serial No. 877,363.

To all whom it may concern:

Be it known that I, OTTO E. DENIVELLE, a citizen of the United States, and a resident of Mount Vernon, in the county of Westchester and State of New York, have invented new and Improved Sleeping-Eyes for Dolls, of which the following is a full, clear, and exact description.

The object of the invention is to provide new and improved sleeping eyes for dolls, arranged to permit each eye to move into open or closed position independently one of the other, to insure free movement of the eyeballs, and to allow of manufacturing the eyes very economically.

In order to accomplish the result, use is made of eyeballs mounted to turn independently one of the other, each eyeball having a balancing weight. Use is also made of metallic sockets cast into the plastic material of the doll's head, each socket having an opening corresponding to the edges of the eyelids, and an eyeball mounted in each socket. Use is further made of an eyeball having a flattened portion, and a disk applied to the said flattened portion and having printed on its face a representation of the iris of the human eye, the portions of the eyeball adjacent the sides of the flattened portions being painted white and the portion of the eyeball above the flattened portion having a flesh color.

A practical embodiment of the invention is represented in the accompanying drawings forming a part of this specification, in which similar characters of reference indicate corresponding parts in all the views.

Figure 1 is a cross section of a doll's head in upright position and provided with the improved sleeping eyes; Fig. 2 is a like view of the same with the doll's head in horizontal position and the sleeping eyes closed; Fig. 3 is a similar view of the same with the doll's head in forwardly inclined position; Fig. 4 is a sectional rear elevation of the doll's head on the line 4-4 of Fig. 1; Fig. 5 is a cross section of a portion of the doll's head at one of the eyes and provided with the eyeball socket and the eyeball removed; Fig. 6 is a perspective view of one of the eyeballs, and Fig. 7 is an enlarged cross section of a portion of one of the eyeballs.

The doll's head A is made of a suitable plastic material and is provided at the eye openings B with spherical sockets C, prefer-

ably of metal cast into the material of the head A at the time the latter is in a plastic condition in the mold, so that the sockets C on the hardening of the plastic material are securely fastened in position in the head A and are not liable to shrink, thus forming a proper bearing for the eyeballs D. Each socket C is provided at the front with an opening C' of almond shape, with the edge corresponding to the edges of the eye opening B, that is, to the edges of the eyeballs. Centrally through the two eyeballs D extends a pivot pin E also passing through the sockets C and the side walls thereof so that the eyeballs are securely held in place and the eyeballs D are axially mounted to turn in the sockets C. The ends of the pin may project beyond the sockets C to be embedded in the plastic material to aid in holding the sockets in place in the head A. Each socket C is slightly in excess of a hemisphere so that the rear portion of each socket is open. Each of the eyeballs D is provided with a counterweight F, preferably in the form of a nail, the angular point of which is driven into the eyeball D so that the nail extends downward, as plainly indicated in the drawings. It will be noticed that by the arrangement described the counterweight F is free of the socket C to turn the eyeball D freely in the socket C whenever the head A is moved from a vertical position into horizontal or inclined position, or vice versa, as will be readily understood by reference to Figs. 1, 2 and 3.

Each of the eyeballs D is preferably made of wood having at its front a flattened portion D' on which is pasted or cemented a disk D² of paper or like material, and having printed thereon a representation of the iris of the human eye. The portions of each eyeball D to the sides and the bottom of the flattened portion D' are provided with a coating of white enamel D³, and the portion of the eyeball D above the flattened portion D' is provided with a coating of flesh color D⁴ so that when the eyeballs are in sleeping position, as shown in Fig. 2, then this flesh-colored portion D⁴ extends in the openings B thereby giving a natural appearance to the sleeping eye. The disk D² as well as the coatings D³, D⁴ are preferably covered with a coating of transparent varnish D⁵ to give the desired luster to the eyes. The balancing weight F is so arranged that when the head A is tilted forward its termi-

nal abuts against the inner face of the head A thus limiting the turning movement of the eyeball D and without moving the iris out of register with the opening C' in the corresponding socket C (see Fig. 3).

From the foregoing it will be seen that by embedding the metallic sockets C in the plastic material of the head A and mounting the wooden eyeballs D in the said sockets 10 the latter are at all times free to turn, thus insuring a quick opening and closing movement of the eyes when moving the head A from vertical into horizontal position or vice versa.

15 It will also be noticed that by the use of the metallic socket C the shrinking of the plastic material during the setting thereof does not cause a shrinking of the sockets and consequently the eyeballs D are not 20 liable to bind in the sockets.

Having thus described my invention, I claim as new and desire to secure by Letters Patent:

1. A doll's head provided with eye sockets 25 cast in the material of the head, eyeballs mounted to turn in said sockets, and a single pivot rod upon which said eyeballs are

mounted to swing, the ends of said rod embedded in the side walls of the head and passing through the sockets and eyeballs, 30 whereby the eyeballs are maintained in proper alinement and position.

2. An eyeball for dolls' heads formed of wood and having a flattened portion and a disk attached to the said flattened portion 35 and having printed on its face a representation of the iris of the human eye.

3. An eyeball for dolls' heads formed of wood and having a flattened portion and a disk attached to the said flattened portion 40 and having printed on its face a representation of the iris of the human eye, the portions of the eyeballs at the sides of the said flattened portion being provided with a coating of white enamel and the portion of the 45 eyeball above the said flattened portion being provided with a coating of flesh color.

In testimony whereof I have signed my name to this specification in the presence of two subscribing witnesses:

OTTO ERNEST DENIVELLE.
